UNITED STATES PATENT OFFICE.

RICHARD M. WATSON, OF DETROIT, MICHIGAN.

LOOSE-LEAF BINDER.

1,075,740.

Specification of Letters Patent. Patented Oct. 14, 1913.

Application filed November 9, 1912. Serial No. 730,310.

To all whom it may concern:

Be it known that I, RICHARD M. WATSON, a citizen of the United States, residing at Detroit, county of Wayne, State of Michigan, have invented a certain new and useful Improvement in Loose-Leaf Binders, and declare the following to be a full, clear, and exact description of the same, such as will enable others skilled in the art to which it pertains to make and use the same, reference being had to the accompanying drawings, which form a part of this specification.

This invention relates to loose-leaf binders and has for its object a loose-leaf binder whose base is constructed of a single piece of metal forming a complete closure for the mechanism that operates the clips.

A further feature of my invention is a novel form of attaching the base of the binder to the book upon which it is to be used.

In the drawings:—Figure 1, is a cross section of the binder showing the clips closed. Fig. 2, is a cross section of the binder showing the clips open. Fig. 3, is a plan view of the binder. Fig. 4, is a sectional detail view of the end of the base of the binder. Fig. 5, is a perspective of a modified form in process of construction. Fig. 6, is a cross section of the same showing the fabric placed upon the base member before the same is bent over for a closure. Fig. 7, shows a cross section of the binder after the base has been closed and the fabric has, thereby, been attached to the binder.

1 and 2 are the conventional forms of clips or half-rings, that are used to hold the leaves and upon which the leaves may be turned. In the form shown in Figs. 1 to 4 inclusive, the clips 1 and 2 are integral portions of wires that form, also, bearing portions 1^a and 2^a. These bearing portions are journaled in the channel bearings 3 and 4 formed at the bends of the base 5. This base 5 is a single piece of sheet metal that is cut at 6 for the passage of the clips and which is bent back upon itself at 7 and 8 to form the bottom closure of the base so as to confine the mechanism that operates the clips, which comprises the bearing portions 1^a and 2^a and a pair of continuations thereof at each end that converge together to form a toggle and with

which the clips are integral. The bearing portions 1^a and 2^a are journaled in the channel bearings 3 and 4.

The portions 7 and 8 (the return strips that are bent back to form a complete closure) may be omitted and the bend of the base confined to a strip that is just sufficient to form the channel bearings 3 and 4. If this form of structure is adopted then the back of the book upon which the binder is used forms the bottom closure to confine the operating mechanism. However, there is an important improvement in providing the portions 7 and 8 so as to form a complete closure as these binders are usually employed in connection with flexible backs and the mechanism is thereby subject to knocks which may knock the base-bearings from their toggle relation and require resetting, which is difficult after the book has been made up.

In the form which I have shown in Figs. 1 to 4, inclusive, the binders are attached to the book by the end portions 9, there being one at each end although only one is shown in the drawings. This end portion 9 is merely a small, somewhat triangular piece of metal that is stamped out when the metal is cut and which is bent down, as shown in Fig. 4, so that the run of the metal that forms the top of the base can reach and rest upon the back of the book to which it is to be fastened. A rivet may then be passed through the aperture 10 and through the back of the book (not shown) to fasten the binder securely thereto.

In Figs. 5 to 7 I have shown a modified form which, however, embodies my generic invention of making the base of the binder out of a single piece of metal, and the generic invention of the base of a single piece forming a complete closure. The clips 1 and 2 are shown fastened to plates 1^b and 2^b. These plates are substituted for the base wires 1^a and 2^a and perform the same function of forming base bearings and a toggle for the clips. These plates 1^b and 2^b meet in a toggle at the center of the binder and are prevented from separating by the rivet 11 that engages loosely in semi-circular cut-away portions of each plate. The spring action necessary to keep the clips opened out or closed together may be afforded either by the resiliency in the metal of the base or spring rivets, such as I have

shown in my application No. 725,359 may be used. The feature of this modified form is the manner of attaching the fabric which is afforded by the structure adopted.

5 Referring to Fig. 5, the base 12 is shown before the sides have been bent over to act as a closure for the plates 1^b and 2^b. The metal is notched by deep notches 12^a, which are of a given width and which are repeated 10 at intervals equal to the width of the notch, forming lugs or prongs 13. The fabric F is slotted as at 14 by portions being cut out of a given length and the slots being repeated at intervals equal to their length.

15 These slots 14 are of the same length as the width of the prongs 13 so that the slots may fit over the prongs or lugs 13, as shown in Fig. 6. The prongs may then be bent down, as shown in Fig. 7 and the fabric 20 F will be effectively secured to the binder and the cut-away portions 12 of the binder, which would ordinarily leave a gap are closed by the fabric F so that the entire structure forms a complete closure for the 25 binder and at the same time does away with such fastening means, as shown in Figs. 1 to 4 or any other fastening means. The fabric F may then be attached to the book in the conventional way and this will of course attach the binder thereto.

It is to be understood that the base bearings, such as 1^a and 2^a, shown in Figs. 1 to 4 and the base bearings 1^b and 2^b, shown in Figs. 5 to 7, inclusive, are merely forms 35 that I have employed in connection with this invention but other forms of base bearings might be employed without altering the structural features that I deem novel in connection with this invention.

What I claim is:—

1. A loose-leaf binder, having in combination, a base plate of sheet metal having the sides of the metal bent back to substantially meet at the back, thereby forming channel bearings on either side and a closure at the 40 back for the base of the binder, and the said metal being also arranged for fastening to the binder, clips or half rings for holding the leaves and bearings therefor, one bearing journaled in each channel bearing and both bearings meeting in a toggle, substantially as described.

2. A loose-leaf binder, having in combination, a base plate of sheet metal having the sides of the metal adapted to be bent back 55 to substantially meet at the back of the base of the binder, thereby forming channel bearings on either side, the said side portions of the metal being notched to form alternate notches 12^a and lugs 13, clips or half rings for holding the leaves, bearings for the clips or half rings, one bearing journaled in each channel bearing and both bearings meeting in a toggle, and a fabric F having 60 two rows of slots that allow the fabric to fit over the lugs when the latter are in upright position, the said lugs being adapted to impinge upon the fabric when bent down and thereby with the fabric forming a complete closure at the back of the base of the 65 binder, substantially as described.

In testimony whereof, I sign this specification in the presence of two witnesses.

RICHARD M. WATSON.
